CLAIM

The ornamental design for an ultra-compact visible spectral sensor case, as shown and described.

DESCRIPTION

FIG. 1 is a perspective view of an ultra-compact visible spectral sensor case showing my new design;

FIG. 2 is a top view of an ultra-compact visible spectral sensor case showing my new design on a reduced scale;

FIG. 3 is a bottom view of an ultra-compact visible spectral sensor case showing my new design on a reduced scale;

FIG. 4 is a front view of an ultra-compact visible spectral sensor case showing my new design;

FIG. 5 is a back view of an ultra-compact visible spectral sensor case showing my new design;

FIG. 6 is a right side view of an ultra-compact visible spectral sensor case showing my new design on an enlarged scale; and,

FIG. 7 is a left side view of an ultra-compact visible spectral sensor case showing my new design on an enlarged scale. The broken lines showing parts of the sensor case in FIG. 3 form no part of the claimed design.

1 Claim, 4 Drawing Sheets
